UNITED STATES PATENT OFFICE.

ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

MEANS FOR SUPPORTING AND LEVELING BRAKES.

1,335,186.

Specification of Letters Patent. Patented Mar. 30, 1920.

Application filed July 29, 1918. Serial No. 247,098.

To all whom it may concern:

Be it known that I, ARMAND H. PEYCKE, a citizen of the United States, residing at Chicago, in the county of Cook and State of Illinois, have invented certain new and useful Improvements in Means for Supporting and Leveling Brakes, of which the following is a specification.

This invention relates to means for supporting and leveling brakes, and more particularly to a third point supporting arrangement.

The object of this invention is to simplify and improve brake supporting and leveling means, and to provide an improved arrangement that will meet the requirements for successful commercial operation.

This and other objects are accomplished by the arrangement shown on the accompanying sheet of drawings, in which—

Figure 1 is a fragmentary side elevation, parts being in section, of a railway car truck embodying my invention.

Fig. 2 is a fragmentary plan view of the same arrangement.

Fig. 3 is a detail plan view of a modified form of my invention.

Fig. 4 is a detail view of the same parts shown in Fig. 3 taken at a different angle, and

Fig. 5 is a side elevation of the members shown in Figs. 3 and 4.

The various novel features of my invention will be apparent from the following description and drawings, and will be particularly pointed out in the appended claims.

Referring to the figures of the drawings, it will be noted that I have shown my invention in connection with a railway car truck, including a spring plank 10 secured to opposite sides of which at each end are combined safety bar brackets and brake beam supporting and leveling members 11. Preferably each of the members 11 has a hooked portion which passes over a vertical flange of the spring plank 10, in addition to being riveted to the spring plank. The lower portions of these members 11 preferably are apertured for the reception of safety bars 12 which underlie the brake beams for the purpose of preventing the brake beams from falling to the track in the event that they become detached from their normal hangings. The safety bars have spring

clips 13 which engage the bracket members 11 to prevent longitudinal movement of the safety bars. Each of the combined bracket and supporting and leveling members 11 has an upper resilient portion 14, which extends over the brake beam including a tension member 15 and a compression member 17, which are held apart intermediate their ends by a fulcrum 18.

It will be understood that the brake beams normally are held at a pre-determined height by two hangers, which in most cases are connected to the brake heads at the ends of the beam. It is well appreciated, however, that with the truss type of brake beam the tension rod portion of the brake beam tends to move into a lower position due to an unbalanced condition. To compensate for this unbalanced condition, the front or tension rod portion of the brake beam must be supported in order that the braking surface of the brake shoes may be maintained in concentric relationship with respect to the braking surface of the associated truck wheel.

By referring to Fig. 2, it will be noted that I have shown four of the combined bracket and supporting members 11, the overhanging portions 14 of which extend outwardly from the spring plank 10 to a point in line with the front end of the fulcrum 18 in each case. By referring particularly to Figs. 1 and 2, it will be noted that the associated lipped ends 19 of the resilient members 14 are connected by a bar 20, which is operatively connected with the front end of the fulcrum 18 for the purpose of balancing the brake beam. The means for operatively connecting the rod 20 to the fulcrum 18 may be varied. My preferred form is shown in Figs. 1 and 2, wherein the member 20 which extends transversely with respect to the car truck, or in the same direction as the brake beam, slopes downwardly from its outer ends to its middle point, at which point there is formed an integral eye portion 21, which is received between the jaws 22 of the fulcrum 18. Through these jaws and through the eye 21 there passes a connecting pin 23. In this manner the brake beam is retained in a balanced condition in a simple manner, the rod 20 acting as a swinging link which is yieldably supported.

In Figs. 3, 4, and 5, I have shown another

rod 24 which may be substituted for the rod 20 shown in Figs. 1 and 2, this present rod 24 also extending downwardly toward its center portion and instead of being connected directly to the fulcrum passes through an aperture 25 in a link 26 having another aperture 27, by means of which the link may be connected to the fulcrum by a suitable pin. If desired, the dip of the rod 10 24 may be increased at its middle point to such an extent that the rod itself might pass through the apertures in the fulcrum jaws.

There may be other modifications of the invention, and it is my intention to cover all 15 such modifications falling within the spirit and scope of the following claims.

What I claim is:

1. In brake mechanism, the combination of 20 a brake beam, and a member extending in the same direction as the brake beam and having a downwardly extending portion operatively connected to said brake beam at an intermediate point thereof for supporting the latter.
2. In brake mechanism, the combination of 25 a brake beam, a resilient member extending over said brake beam, and a member connected to said resilient member and extending in the same direction as the brake beam and being operatively connected to the latter at an intermediate point thereof for holding the brake beam in a balanced position.
3. In brake mechanism, the combination of 30 a brake beam, oppositely arranged members located intermediate the ends of the brake beam and extending transversely over the latter, and a member connected to said oppositely arranged members and being operatively connected to the brake beam for supporting the latter in a balanced position.
4. In brake mechanism, the combination of 35 a brake beam having tension and compression members, a fulcrum connecting same, and a member extending in the same direction as the brake beam and having a downwardly extending portion operatively connected to the fulcrum for supporting the brake beam in a balanced position.

5. In brake mechanism, a brake beam supporting member supported at its opposite ends extending substantially from one side of the truck to the other and having intermediate its ends an eye portion operatively connected to the brake beam for supporting 55 the latter.

6. In brake mechanism, the combination of a brake beam having tension and compression members, a fulcrum extending therebetween, and a member extending 60 transversely of the car supported at more than one point and having an eye portion operatively connected to the fulcrum member for balancing the brake beam.

7. In brake mechanism, the combination 65 of a brake beam, a supported bracket member, a safety bar connected to said bracket member and underlying the brake beam, said bracket member having a portion overhanging said brake beam, and a member 70 connected to the overhanging portion and extending in the same direction as the brake beam and having a portion operatively connected to the brake beam for supporting the latter.

8. In brake mechanism, the combination of a brake beam, a safety bar underlying the brake beam for preventing the latter from falling to the track, a member connected to the safety bar and extending over the brake 80 beam, and means supported by said member and extending in the same direction as the brake beam and having a portion operatively connected to the brake beam to hold the latter in a balanced position. 75

9. In brake mechanism, the combination of a brake beam, safety bars underlying the brake beam near the opposite ends thereof, a plurality of spaced members extending over said brake beam and connected to the safety 90 bar, and a member connected to said spaced members and having a portion operatively connected to the brake beam for supporting the latter.

Signed at Chicago, Illinois, this 19th day 95 of July, 1918.

ARMAND H. PEYCKE.
